UNITED STATES PATENT OFFICE.

WILBER E. SARGEANT, OF MONROVIA, CALIFORNIA.

BUILDING FOR GARBAGE-RECEPTACLES.

1,182,799.

Specification of Letters Patent.

Patented May 9, 1916.

Application filed April 30, 1915. Serial No. 25,054.

To all whom it may concern:

Be it known that I, WILBER E. SARGEANT, a citizen of the United States, residing at Monrovia, in the county of Los Angeles and 5 State of California, have invented certain new and useful Improvements in Buildings for Garbage-Receptacles, of which the following is a specification.

This invention relates to an improvement 10 in receptacles or buildings in which garbage-receptacles, cans, and the like may be stored for the purpose of keeping the garbage-receptacles away from insects.

In localities where flies are a nuisance, 15 and affect conditions around apartment-houses and the like, as for instance on the Pacific Coast, it has been found that where the garbage-receptacles were left on the outside of the building where flies could come 20 in contact with them, the insects would make conditions very disagreeable for the occupants of the buildings or apartments. To overcome this objection, a building is provided which will be ventilated, and at 25 the same time arranged so that the insects will have no means of ingress. If, however, the insects should enter the receptacle when the garbage cans are being placed in the receptacle, an outlet is provided which the 30 flies will seek, and after passing through the outlet they cannot return.

In the accompanying drawings:—Figure 1 is a vertical sectional view through the building; Fig. 2 is a horizontal sectional view; Fig. 3 is a vertical sectional view through terra-cotta thimble and fly-trap screen; and Fig. 4 is a detail sectional view showing the manner of mounting the screen upon the door.

40 A, represents the wall of the building which is made entirely of concrete, and 1 represents the concrete flooring. The wall A has one opening 2 formed therein, which forms the door-way in which is mounted a 45 door 3. This door is provided near its bottom with an elongated slot 4, and covering this slot or opening 4 is a fine mesh screen 5 for the purpose of admitting air to the interior or chamber of the building.

The roof 6 is also made of concrete, and is 50 mounted upon the wall A, and is provided with an orifice 7 in which is mounted the terra-cotta thimble 8, the thimble being placed in position during the formation of the roof, so that it is securely held in place 55 by the concrete. An air-pipe made of galvanized iron 9 is mounted upon the thimble, and at the top of the pipe 9 a cowl or cap 10 is connected for preventing moisture from passing down the pipe and into the chamber. 60 The thimble 8 is provided with a fly-trap which consists of a galvanized iron band 11 which has a flange 12 thereon, the flange engaging the lower surface of the thimble while the band 11 engages the inner 65 wall of the thimble for maintaining the band in position in the thimble. A cone-shaped screen 13 is connected to the band, and is provided with an orifice 14 at its periphery. The opening 4 in the door and 70 the pipe 9 provide means whereby air can circulate through the building and relieve it of any odors which may be thrown off by the garbage placed therein. If any insects, such as flies, enter the receptacle or chamber 75 when the door is opened for the purpose of placing the receptacles in the building, or upon the removal of the receptacles from the building for the purpose of emptying them, the flies will naturally seek an outlet. 80 The building being dark, and the light only entering the chamber at the top and bottom, the rays of light coming through the air-pipe 9 will attract the insects, and as they enter the cone-shaped screen they will find 85 an outlet through the orifice 14, and after passing through this orifice, it will be impossible for them to return.

I claim:

The combination with a building consisting of walls and roof, said walls provided with an opening, of a door mounted within the opening and normally maintained in a closed position for keeping the building in a darkened condition, said door provided 90 with an opening therein, a screen covering said opening for admitting air to the building, a thimble formed in the roof, an air-

pipe having a cowl thereon mounted upon the thimble, a band received in the thimble and held therein by friction, and a screen connected to the band having an opening 5 therein through which insects may pass from the chamber of the building into the air-pipe.

In testimony whereof I affix my signature, in the presence of two witnesses.

WILBER E. SARGEANT.
